(57) **CLAIM**

The ornamental design for a bike tent, as shown and described.

DESCRIPTION

FIG. 1 is a perspective view of a bike tent showing my new design;

FIG. 2 is another perspective view thereof;

FIG. 3 is a front elevational view thereof;

FIG. 4 is a rear elevational view thereof;

FIG. 5 is a left elevational view thereof;

FIG. 6 is a right side view thereof;

FIG. 7 is a top side view thereof;

FIG. 8 is a bottom plan view thereof;

FIG. 9 is a perspective view of FIG. 1 showing that the front flap of the bike tent is in its open position and the window vent is in its rolled up position;

FIG. 10 is a perspective view of FIG. 2 showing that the front flap of the bike tent is in its open position and the window vent is in its rolled up position;

FIG. 11 is a partial enlarged view of FIG. 1;

FIG. 12 is a partial enlarged view of FIG. 1;

FIG. 13 is a partial enlarged view of FIG. 1;

FIG. 14 is a partial enlarged view of FIG. 1;

FIG. 15 is a partial enlarged view of FIG. 2;

FIG. 16 is a partial enlarged view of FIG. 2;

FIG. 17 is a partial enlarged view of FIG. 2;

FIG. 18 is a partial enlarged view of FIG. 9;

FIG. 19 is a partial enlarged view of FIG. 10;

FIG. 20 is a perspective view of FIG. 10 with the combination of two bike tents; and,

FIG. 21 is a perspective view of FIG. 10 with the combination of three bike tents.

The broken lines in the figures are for the purposes of illustrating portions of the bike tent, which form no part of the claimed design. The broken lines showing a tent in FIGS. 20 and 21 are for the purposes of illustrating environment and form no part of the claimed design.

1 Claim, 17 Drawing Sheets
